UNITED STATES PATENT OFFICE

93,917

DESIGN FOR A WAFFLE IRON GRID

Philip A. Eyrick, Arlington, Mass.

Application October 1, 1934, Serial No. 53,450

Term of patent 14 years

To all whom it may concern:

Be it known that I, PHILIP A. EYRICK, a citizen of the United States, residing at Arlington, in the county of Middlesex and State of Massachusetts, have invented a new, original, and ornamental Design for a Waffle Iron Grid, as shown in the accompanying drawing and described in the following specification.

In the drawing:

Figure 1 is a plan view of the waffle iron grid showing my new design; and

Figure 2 is a cross section of the device shown in Figure 1.

The bosses constituting the design elements in the several quadrants have flat tops with sloping sides.

I claim:

The ornamental design for a waffle iron grid, as shown and described.

PHILIP A. EYRICK.
